US00D970835S

(12) **United States Design Patent** (10) **Patent No.:** **US D970,835 S**
(45) **Date of Patent:** **** Nov. 22, 2022**

(54) **VACUUM CLEANER SUCTION TUBE**

(71) Applicant: **fischer Rohrtechnik GmbH**, Achern-Fautenbach (DE)
(72) Inventors: **Stephan Cordes**, Achern-Fautenbach (DE); **Dirk Müller**, Achern-Fautenbach (DE)
(73) Assignee: **fischer Rohrtechnik GmbH**, Essen (DE)

(**) Term: **15 Years**

(21) Appl. No.: **29/726,465**

(22) Filed: **Mar. 3, 2020**

(30) **Foreign Application Priority Data**

Sep. 3, 2019 (EM) 006810883

(51) **LOC (13) Cl.** **15-05**

(57) **CLAIM**

The ornamental design for a vacuum cleaner suction tube, as shown and described.

DESCRIPTION

FIG. 1 is a left side perspective view of a vacuum cleaner suction tube in accordance with the new design;

FIG. 2 is a right side perspective view thereof;

FIG. 3 is a top plan view thereof;

FIG. 4 is a front elevation view thereof;

FIG. 5 is a left side elevation view thereof;

FIG. 6 is a right side elevation view thereof;

FIG. 7 is a bottom plan view thereof; and,

FIG. 8 is a rear elevation view thereof.

The broken lines shown in the drawing figures depict portions of the vacuum cleaner suction tube that form no part of the claimed design.

1 Claim, 4 Drawing Sheets
